UNITED STATES PATENT OFFICE.

WILLIAM WEBSTER PRICE, OF ELM GROVE, WEST VIRGINIA.

VALVE-REMOVING TOOL.

1,218,460.

Specification of Letters Patent.

Patented Mar. 6, 1917.

Application filed May 5, 1916. Serial No. 95,678.

To all whom it may concern:

Be it known that I, WILLIAM W. PRICE, a citizen of the United States, residing at Elm Grove, in the county of Ohio and State of 5 West Virginia, have invented new and useful Improvements in Valve-Removing Tools, of which the following is a specification.

This invention relates to valve removing 10 tools or more particularly to the class of tools used for compressing the springs which hold puppet valves upon their seats, in order that the spring retaining pin may be readily removed from the stem of the valve and as 15 readily replaced therein, this being necessary in order to remove the valve from an engine which is ordinarily done for the purpose of regrinding the faces of the valve and valve seat.

20 With the above and other objects in view, the invention consists in the novel construction, combination and arrangement of parts, as herein described, illustrated and claimed.

In the accompanying drawings:—

25 Figure 1 is a perspective view of the complete tool.

Fig. 2 is a cross section through the same taken adjacent to the yoke ring.

30 Fig. 3 is a fragmentary section through an internal combustion engine, showing one of the engine valves and the valve seating spring and illustrating the initial position of the valve removing tool of this invention.

35 Fig. 4 is a view similar to Fig. 3 showing the final position of the tool.

The tool contemplated in this invention comprises only three parts, 1 designating the base of the tool, 2 the lever and 3 a yoke ring 40 by means of which the members 1 and 2 are adapted to be properly positioned in relation to each other and the lever operated for compressing the valve seating spring.

45 4 designates a fragment of an engine, 5 one of the valves thereof, 6 the valve seat, 7 the valve spring, 8 the valve stem, and 9 the spring retaining pin which is as usual inserted through a hole in said stem, all of 50 said parts relating to the engine being of the usual construction and arrangement. The tool member 1 is practically straight

throughout but the inner end thereof is flattened and expanded in width to form a comparatively thin head 12 which is provided with an open ended slot 13 adapted to embrace the push rod or push rod bushing above referred to in the manner indicated in Figs. 3 and 4. The lever member 2 has its corresponding end made of less thickness and is laterally expanded to provide a relatively wide head 14 which like the member 1 is formed with an open ended slot 15 so that it may straddle the valve stem 8 and engage the lower end of the valve spring 7 in the manner illustrated in Fig. 4. The inner end portion of the lever 2 is arched, deflected or curved as shown at 16 so that the head 14 thereof will be practically horizontal when the parts of the tool are in their final position as indicated in Fig. 4, thereby holding the spring 7 compressed 65 while the pin 9 is being removed or replaced in its relation to the valve stem 8.

In operation, the lever 2 and the ring 3 are slid backwardly a suitable distance on 75 the base member 1 as illustrated in Fig. 3. The head 12 is then thrust under the pin 9 and around the push rod 10 or the bushing 11. Then the pointed extremity of the head 14 is thrust under the lower end of the 80 spring 7. With the yoke ring 3 in the relation to the lever 2 as shown in Fig. 3, the outer end portion or handle of the lever is then rocked toward the handle end of the base member 1 and as the lever 2 fulcrums 85 on the upper surface of the member 1, the spring 7 is compressed until it assumes the position illustrated in Fig. 4. The yoke 3 is then slid outwardly toward the handle portions of the members 1 and 2 and serves 90 to lock the handle portions of the two members together thereby maintaining the members 1 and 2 in the relation shown in Fig. 4. This enables the operator to use both hands in removing the pin 9. After this is done, 95 the ring 3 is again moved into the relation to the member 2 shown in Fig. 3. The member 2 together with the ring 3 are then slid outwardly toward the handle end of the member 1 and the tool as a whole with- 100 drawn from its useful position. This releases the spring 7 and enables the valve

5 and its stem to be drawn upwardly. The same operation is carried out when it becomes necessary to reinsert the pin 9.

I claim:—

- 5 A tool of the class specified, comprising a base member having a slot in one end thereof, a lever member having a portion thereof offset so as to fulcrum on the base member and also provided with a slot in the end

thereof, and a yoke ring slidable lengthwise of the base and lever members and adapted to hold the lever member in rocking relation to the base member in one position, and to prevent rocking movement of the lever member when in another position. 15

In testimony whereof I affix my signature.

WILLIAM WEBSTER PRICE.
